(57) **CLAIM**

The ornamental design for a pegboard adapter, as shown and described.

DESCRIPTION

FIG. 1 depicts a perspective view of one embodiment of a pegboard adapter showing my new design.

FIG. 2 depicts a front view of the pegboard adapter of FIG. 1.

FIG. 3 depicts a rear view of the pegboard adapter in FIG. 1.

FIG. 4 depicts a top view of the pegboard adapter in FIG. 1.

FIG. 5 depicts a bottom view of the pegboard adapter in FIG. 1.

FIG. 6 is a left side view of the pegboard adapter in FIG. 1, the right side view being a mirror image thereof;

FIG. 7 depicts one perspective environmental view of the pegboard adapter in FIG. 1.

FIG. 8 depicts another perspective environmental view of the pegboard adapter in FIG. 1.

FIG. 9 depicts a perspective view of another embodiment of a pegboard adapter showing my new design.

FIG. 10 depicts a front view of the pegboard adapter of FIG. 9.

FIG. 11 depicts a rear view of the pegboard adapter in FIG. 9.

FIG. 12 depicts a top view of the pegboard adapter in FIG. 9.

FIG. 13 depicts a bottom view of the pegboard adapter in FIG. 9.

FIG. 14 is a left side view of the pegboard adapter in FIG. 9, the right side view being a mirror image thereof;

FIG. 15 depicts a perspective view of another embodiment of a pegboard adapter showing my new design.

FIG. 16 depicts a front view of the pegboard adapter of FIG. 15.

FIG. 17 depicts a rear view of the pegboard adapter in FIG. 15.

FIG. 18 depicts a top view of the pegboard adapter in FIG. 15.

FIG. 19 depicts a bottom view of the pegboard adapter in FIG. 15.

FIG. 20 is a left side view of the pegboard adapter in FIG. 15, the right side view being a mirror image thereof;

FIG. 21 depicts a perspective view of another embodiment of a pegboard adapter showing my new design.

FIG. 22 depicts a front view of the pegboard adapter of FIG. 21.

FIG. 23 depicts a rear view of the pegboard adapter in FIG. 21.

(Continued)

FIG. 24 depicts a top view of the pegboard adapter in FIG. 21.

FIG. 25 depicts a bottom view of the pegboard adapter in FIG. 21; and,

FIG. 26 depicts a left view of the pegboard adapter in FIG. 21. The right side view is identical.

The broken lines shown in the figures illustrate environmental subject matter or portions of the article that form no part of the claimed design.

The pegboard adapter is shown with a symbolic break in its length or height. The appearance of any portion of the article between the break lines forms no part of the claimed design.
